UNITED STATES PATENT OFFICE.

FREDERICK B. LEOPOLD, OF PITTSBURGH, PENNSYLVANIA.

MULTIPLE OPERATING VALVE.

Application filed June 28, 1923. Serial No. 648,404.

To all whom it may concern:

Be it known that I, FREDERICK B. LEOPOLD, a citizen of the United States, and resident of Pittsburgh, in the county of Allegheny and State of Pennsylvania, have invented a new and useful Improvement in Multiple Operating Valves; and I do hereby declare the following to be a full, clear, and exact description thereof.

10 My invention relates to apparatus for operating hydraulic valves controlled from a distance in filtration or other plants where a device of this kind is applicable.

The present form of apparatus generally employed consists of a large, expensive table usually provided with a marble top on which the operating-handles which connect up to four-way valves inside the table are disposed, which in turn are connected to the 20 manifold header supplying water under pressure to each four-way valve, and carrying away the drain from them. The four-way valves in turn are connected up to each end of the cylinder of the hydraulic valve 25 and the pressure and drain line of the manifold. This construction requires a handle for each valve, and the object of my invention is to eliminate the use of such a large table with the individual four-way valves 30 and manifolds, and thereby economizing both in space and cost, while at the same time greatly simplifying the construction.

In the accompanying drawings, Fig. 1 is a vertical elevation of my improved apparatus with the upper portion in section showing the internal construction and showing the pipe connections to the cylinder for operating the valve; Fig. 2 is a plan view; Fig. 3 is a plan view of the valve case with 40 the top part removed, and Fig. 4 is an enlarged view of a portion of the top indicating plate.

In the drawing the numeral 2 designates a suitable stand or pedestal. Resting on 45 said stand 2 is the valve casing 3 provided with the valve-chambers 4 and 5. Within the valve-chambers 4 and 5 are the valves 6 and 7, respectively, said valves being of piston form fitting snugly within the valve-chambers, and provided with the stems 8 50 which pass up through the top-plate 9 of the valve casing, and through stuffing boxes 10. Pinions 11 are mounted on the outer ends of the stems 8, and said pinions mesh 55 with the central pinion 12 mounted on the vertical shaft 13, said shaft being journaled

at its lower end in the boss 14, and the upper end of said shaft entering the socket 15 in the lever-handle 16. It will be apparent that when the lever 16 is moved a rotary motion will be imparted to the pinion 12 and, through said pinion, to the pinions 11 and valves 6 and 7 connected thereto.

The valves 6 and 7 are provided with the ports 17 and 18, and said ports are adapted to be brought into register with ports 19 and 20 in the bottom-plate 21 of the valve-casing. Pipes 22 and 23 connect up to the ports 19 and 20, respectively, the pipes 22 leading to the lower end of the cylinder 24, while pipes 23 enter the upper end of said cylinder. The piston 25 of the cylinder 24 is connected up to a gate in the ordinary gate-valve 26. It will be understood that while only one gate-valve is illustrated there 75 will be a gate-valve for each pair of pipes 22 and 23.

Ports 27 and 28 formed in the valve casting communicate with the valve chambers 4 and 5, and said ports are controlled by an ordinary plug-valve 29 which is operated by the handle 30. Fluid pressure is admitted by the pipe 31, and the fluid is directed by the valve 29 either through the port 27 or 28 according to the position of the valve 29.

Ports 32 and 33 also lead into the valve-chambers 4 and 5, and said ports are controlled by a plug-valve 34 which opens and closes communication between said ports and the drain-pipe 35. The plug valve 34 is operated by a handle similar to the handle 30.

A hood 36 rests on the stand 2, and said hood encloses the valve-casing and other parts above described.

Formed integral with the socket-portion 95 15 of the operating lever 16 are the indicator fingers 37, each of which bears a legend designating one of the valves of the system. By moving the lever 16 the fingers 37 are brought into register with the point 100 38 on the hood 36 when any one of the valves corresponding to the legend is to be operated.

Mounted on the top of the hood 36 are indicator plates 39 and 40, one for fluid pressure supply and one for the drain.

In the operation of the device, the main lever 16 is rotated to the point indicating the valve that it is desired to operate, thus bringing the ports 17 and 18 of the valves 110 6 and 7 over the corresponding openings 19 and 20 leading to the top and bottom of

the hydraulic cylinder of the valve to be operated.

If it is desired to open the gate-valve 26, the handle of the drain valve is positioned as shown in Fig. 4, so that its notch is at "open" position, while the pressure valve is moved 180° from the position shown in said figure, until its notch is at "open" position. The water will then enter the chamber 4 through the inlet port 27 under pressure and will pass by the port 17 and pipe 22 to the lower end of the cylinder 24. The gate valve 23 will be raised and the water contained in the upper part of the cylinder 24 will pass up through the pipe 23 into the valve chamber 5 and thence by the port 33 to the drain pipe 35. To close the gate-valve 26 it is only necessary to turn the drain valve to closed position and turn the pressure valve to the position shown in Fig. 3, when the reverse action will take place, the pressure being applied to the top of the cylinder 24 and the bottom being connected up to the drain.

25 I claim as my invention:

1. Valve structure comprising a valve casing having a pair of valve chambers therein, a plurality of annularly arranged ports in an end wall of each of said chambers, a fluid pressure port and a drain port in the side wall of each of said chambers, a rotatable valve disc fitting against the end wall of each of the chambers and having a port positioned to register with said annularly disposed ports successively, each of the annularly arranged ports in one chamber having paired relation with a port in the

other chamber, means for rotating said discs in definite relative relation, a source of fluid pressure, a valve for effecting communication between said source and said pressure ports selectively, and a valve for opening and closing said drain ports selectively, means disposed exteriorly of the casing, for rotating said disc, and means disposed exteriorly of the casing for operating said valves.

2. Valve structure comprising a valve casing having a pair of valve chambers therein, a plurality of annularly arranged ports in an end wall of each of said chambers, a fluid pressure port and a drain port in the side wall of each of said chambers, a rotatable valve disc fitting against the end wall of each of the chambers and having a port positioned to register with said annularly disposed ports successively, each of the annularly arranged ports in one chamber having paired relation with a port in the other chamber, means for rotating said discs in definite relative relation, a source of fluid pressure, a valve for effecting communication between said source and said pressure ports selectively, and a valve for opening and closing said drain ports selectively, the said disc rotating means and the said valves being connected to operating handles that are mounted upon the top of the casing.

In testimony whereof I, the said FREDERICK B. LEOPOLD, have hereunto set my hand.

FREDERICK B. LEOPOLD.
